BUILDING BLOCK

Walter S. Rugg, Pittsburgh, and Henry D. James,
Edgewood, Pa.

Application December 22, 1937, Serial No. 181,141

7 Claims. (Cl. 72—16)

The present invention relates to a building unit, and more particularly to a self-contained article of manufacture embodying desired characteristics.

It is the usual practice in the fabrication of buildings and particularly their exterior walls to construct these walls in layers to obtain the desired structural and thermal characteristics. In all cases of which we are aware, this has been accomplished by fabricating the wall on the job by cutting, sawing and fitting large sheets of insulation material to the framework and adding a weather resisting surface of brick, tile, boards, or similar material, which involves a substantial expenditure of time and results in a high labor cost.

Frequently the insulation is inside of the frame or between frame members which is undesirable when the frame is metal.

Recognizing the limitations in present and past practice, applicants have devised an outside wall unit having thermal and sound insulation protected from moisture, and a weather resisting covering combined with structural and decorative features which may be manufactured, merchandised and distributed through existing trade channel, such as are ordinary ceramic bricks. These blocks may be attached to the building framework readily and without fitting to form a tight, weatherproof, insulating covering entirely surrounding the framework. This covering may later be removed for alterations to the building without injury to the blocks. This results in a substantial simplification of the construction of the outside wall of a building with a marked decrease in labor expenditure without sacrificing desired structural and insulating characteristics.

This application is a further development of a system for pre-fabricating houses as disclosed in co-pending application, for Standardized building units, Serial No. 141,438, filed May 8, 1937, by the present inventors.

The object of the invention, therefore, is to provide, as an article of manufacture, building units of standard size for convenient handling which are constructed so as to embody desired insulating, weather resisting and decorative features.

Other objects of the invention will be apparent from the following description read in conjunction with the accompanying drawing wherein:

Figure 1 is a view in perspective of a building block constructed in accordance with the invention, and

Fig. 2 is a view in vertical section taken transversely of the block shown in Fig. 1.

Referring more particularly to the drawing, the building block in accordance with the invention includes a base or pan 2 having angularly upturned edges 4 on each of its sides. The base is preferably of more or less rigid material, such as sheet iron, but may be of any desired material so long as sufficient mechanical strength is provided. It has been found that a convenient size for the base, to facilitate handling of the building unit and insure sufficient flexibility in covering the building wall around door and window openings is two-by-three feet. Of course this size may be varied, but it is contemplated that a single standard size, or a very few standard sizes, shall be adopted to obtain the economies of mass production, stocking and handling.

A body or sheet 6 of thermal and sound insulating material shaped to fit within the lateral confines of the base 2, is suitably secured thereto, such as by a waterproof gum or cement, or it may be molded in position. The insulating material may be of many different types depending upon the degree and kind of insulation required, but is preferably of such character that it is self-supporting so that the gum or cement renders it and the pan a substantially integral unit. Materials now on the market such as "Celotex" or cork may be suitable for this purpose, and the adhesive material may be an asphalt cement, for example, or waterproof glue.

The upper peripheral edge of the sheet 6 is recessed or grooved, as indicated more clearly in Fig. 2, for receiving the depending peripheral edge of the face of the block as hereinafter described, and the top of the sheet is covered with a heat reflecting material 8, such as aluminum foil, suitably glued or cemented thereto.

The face of the block is formed of a desired weather-resistant facing 10. This may be in one piece as indicated in the drawing, and provided with depending edges snugly fitting in the notched edge of the insulation 6. The facing 10 may then be cemented in the position shown, to complete the substantially integral composite block.

The material of the facing 10 may take various forms. It may be of glass, colored, if desired, or transparent in which event reliance may be placed on coloring the reflecting strata 8 to obtain a desired effect. Also the facing may be grooved or corrugated to obtain a desired appearance. Other materials of course are available, and may be used, for the facing, such as tile, metal, or various types of composition material such as "Transite" and "Masonite".

A usual defect in insulating materials, of the

55

kind usually employed, is that they are not free of moisture, or if moisture is initially removed, the material will absorb it from the atmosphere, or other sources, during subsequent use thereby substantially reducing the insulating qualities.

- 5 To remedy this condition, it is contemplated that the block assembled as above described will have the moisture removed initially and the edges of the block sealed to prevent subsequent absorption. The removal may be accomplished by heating the block to thoroughly dry it, and the edges may then be sealed by dipping them in a suitable compound, such as tung oil, waterproof cement, or other moisture-proof material. In the 10 case of relatively dense insulating material, the block may be subjected to a vacuum treatment to insure penetration of the sealing material. The edge of the block when the sealing material has penetrated the insulation, is indicated in Fig. 2. 15
- 15 The assembled unitary and treated block may be secured in operative position, referring to Fig. 2, by means of wedges 12 driven through clips 14, secured to the metal base 2 by rivets, bolts or welding, into engagement with the edge of angles 20 constituting the studding of the building. The securing means shown is illustrative of many which may be employed, but preferably the means should be such that the blocks may be individually removable to facilitate individual replacement if 25 required.

20 After the blocks are in position, suitable cement or caulking may be applied to the cracks between them to insure moisture-tight joints.

- 25 It is considered that the present invention is a real advance in the building art. It makes possible a complete building exterior fabricated in the factory and hence minimizes high labor cost on the job. It provides a complete insulated and weather-resistant wall structure while retaining the advantage of handling individual units in much the same manner as ordinary building brick. It affords a standardizable unit with attendant economies in manufacture and distribution. The blocks constitute a unit for an exterior 30 wall, which when assembled, the whole constitutes a complete exterior wall having all of the characteristics desirable for such a wall; namely, weather resisting; heat and sound insulating, nonabsorbent of moisture; the whole wall being exterior 35 to the frame of the building leaving the spaces between the frame members available for air ducts, pipes, conduits, etc.; and with no heat conducting parts extending from the outside surface to the frame.

- 40 55 Modifications may be made in the specific materials described and it is intended that the scope of the invention shall not be limited except by the scope of the appended claims.

We claim as our invention:

- 45 60 1. As an article of manufacture, a building block for an exterior wall comprising a metallic pan, a layer of thermal insulating material covering the entire area of one side of said pan, a weather-resistant facing on said insulating material and spaced from said pan, and means for securing said pan, layer and coating in assembled relation to constitute a unitary structure; said layer of insulating material being substantially 65 free of moisture and means sealing the edges thereof in moisture-tight manner.

5 6 2. As an article of manufacture, a building block for an exterior wall comprising a metallic pan, a layer of thermal insulating material covering said pan, a sheet of heat reflecting material covering said insulating material, a weather resistant body covering said reflecting material, and means for cementing said elements together to constitute an integral building block with no metallic conducting path between said pan and the exposed surface of said weather-resistant body. 10

15 3. As an article of manufacture, a building block for an exterior wall comprising a metallic pan, a layer of thermal insulating material covering said pan, a sheet of heat reflecting material covering said insulating material, a weather resistant body covering said reflecting material, and means for cementing said elements together to constitute an integral building block; said layer of insulating material being substantially free of moisture and means sealing the edges thereof in 20 moisture-tight manner.

25 4. As an article of manufacture, a building block for an exterior wall comprising a rigid, fire-proof, nonabsorbent base, a layer of thermal insulating material covering said base, a weather-resistant facing on said insulating material, and means for securing said base, layer and facing in assembled relation to constitute a unitary structure; said base having up-turned edges embracing the edges of said layer of insulating material, and said weather resistant coating being non-flexible and having depending edges embracing the edges of said insulating material. 30

35 5. As an article of manufacture, a building block for an exterior wall comprising a base plate having upturned edges, a body of insulating material disposed on said plate and having only its lower edges embraced by the edges of the plate, a heat reflecting sheet covering the upper face of the body, a layer of weather resistant material 40 covering said sheet, and means for securing said elements in the relation specified to constitute a unitary block.

45 6. As an article of manufacture, a building block for an exterior wall comprising a metallic base plate, a layer of thermal insulating material completely covering one side of said plate, a weather-resistant body on said insulating layer and spaced by said layer over its entire area by said layer from said plate, and means for securing said base, layer and body in assembled relation to 50 constitute a unitary structure.

55 7. An article of manufacture comprising a building block for an exterior wall comprising a metallic base plate of rectangular shape, a layer of thermal insulating material completely covering one side of said plate, a weather-resistant body material covering the surface of said thermal insulation layer coextensive with the lateral dimensions thereof and being spaced thereby from 60 the entire said side of said plate and out of thermal conducting relation therewith, and means for securing said base plate, layer of thermal insulation and weather resistant material in assembled relation in such manner that there is no metallic 65 heat conducting path from the base plate to the weather-resistant material, and means secured to said base plate for securing the block to a support.
